[57] CLAIM

The ornamental design for a disk drive module for redundant arrays, as shown and described.

DESCRIPTION

FIG. 1 is a front perspective view of a disk drive module for redundant arrays showing our new design;

FIG. 2 is a front elevation view of FIG. 1;

FIG. 3 is a left side elevation view of FIG. 1;

FIG. 4 is a right side elevation view of FIG. 1;

FIG. 5 is a rear elevation view of FIG. 1;

FIG. 6 is a top plan view of FIG. 1; and,

FIG. 7 is a bottom plan view of FIG. 1.
